UNITED STATES PATENT OFFICE.

WILLIAM WATTIE, OF WORCESTER, MASSACHUSETTS, ASSIGNOR TO CROMPTON & KNOWLES LOOM WORKS, A CORPORATION OF MASSACHUSETTS.

MACHINE FOR CUTTING SPIRAL OIL-CHANNELS IN BOXES, BEARINGS, &c.

No. 872,036.

Specification of Letters Patent.

Patented Nov. 26, 1907.

Application filed July 1, 1905. Serial No. 267,905.

To all whom it may concern:

Be it known that I, WILLIAM WATTIE, a citizen of the United States, residing at Worcester, in the county of Worcester and State of Massachusetts, have invented certain new and useful Improvements in Machines for Cutting Spiral Oil-Channels in Boxes, Bearings, &c., of which the following is a specification.

10 My invention relates to a machine for cutting spiral oil channels in boxes, bearings, etc., and particularly relates to a supplemental attachment or mechanism, adapted to be combined with and used on the key 15 seating machine, shown and described in U. S. Letters Patent, No. 275,393.

The object of my invention is to provide mechanism for cutting spiral oil channels in boxes, bearings, etc., said mechanism being 20 adapted to be used in connection with said patented machine.

My invention consists in certain novel features of construction of my improvements, as will be hereinafter fully described.

25 I have shown in the drawings sufficient portions of said patented machine, with my improvements combined therewith, to enable those skilled in the art to understand the construction and operation thereof.

30 Referring to the drawings:—Figure 1 is a side view of said patented machine, with my improvements combined therewith. Fig. 2 is, on an enlarged scale, a vertical sectional view of the parts shown at the left in Fig. 1.

35 Fig. 3 corresponds to Fig. 2, but shows some of the parts in a different position, and also shows the spindle in section. Fig. 4 is a longitudinal sectional view of a box or bearing, showing a spiral groove cut therein by 40 my improvements. Fig. 5 shows the guiding spindle or pin, and supporting yoke, detached.

In the accompanying drawings, 1 is the bed of the machine, having supporting legs 45 2, and upon the upper surface of the bed 1, ways or guides for the longitudinally reciprocating rack bar 3, which has thereon a block 4 having a hole therethrough, and a set screw or bolt 5 for securing the end of the 50 spindle 6 to said block. The rack bar 3 has a longitudinal reciprocating movement communicated thereto by a pinion 7, fast on a shaft 8, mounted in suitable bearings 9 on the bed 1 of the machine. Also fast on the 55 shaft 8 is a gear 10, which is in mesh with and

driven by a pinion, not shown, fast on the shaft 11 mounted in bearings 11' secured to the underside of the bed 1. On the shaft 11 is fast a belt pulley 12, driven by a belt, not shown, to rotate the shaft 11, the pinion 60 thereon, not shown, the gear 10, and the pinion 7, to move the rack bar 3, in the usual way.

On the front end of the bed 1 of the machine is secured an upright stand 13, having 65 a threaded hole therethrough to receive a bushing 14, see Fig. 2.

All of the above mentioned parts may be of the same construction as similar parts shown and described in said Letters Patent, 70 No. 275,393.

I will now describe my improvements.

Upon the bed 1 of the machine, between the holding block 4 on the rack bar 3, and the stand 13, is secured, in this instance by 75 bolts 15, a box or bearing 16, having in this instance its inner surface 16', of softer metal, with longitudinal spiral shaped grooves upon its inner surface, to receive the longitudinal spiral shaped threads 6' on the rotary 80 spindle 6.

The inner end of the rotary spindle 6 is turned down, and extends loosely through a sleeve 18, which is held on the turned down end of the spindle 6, by a collar 19. The 85 sleeve 18 is secured within the hole through the block 4 by the set screw 5. The outer end of the spindle 6 has in this instance a screw threaded hole 6'' therein, to receive the screw threaded end 20' of the cutting spindle 90 20, which extends loosely through the bushing 14, see Fig. 2. A nut 21 on the threaded end 20' of the spindle 20, and turned up against the end of the spindle 6, secures the spindle 20 to the spindle 6. 95

The cutting spindle 20 has a central longitudinal hole 20'' therein, into which loosely extends a guide spindle or pin 22, which is attached at its outer end to a yoke 23. In this instance the outer end of the pin 22 is 100 turned down and threaded, and extends through a hole in the outer end of the yoke 23, and has a nut 24 thereon.

The guide pin 22 is turned down at its central portion, forming the reduced portion 22' 105 with inclined ends 22'', and also at its inner end, leaving the incline 22''.

In connection with the spindle 20, and the guide pin 22, is used a cutting tool 25, which in this instance is secured in a lever or sup- 110

port 26, which extends in a slotted or recessed portion 20" in the spindle 20, and is pivotally mounted at one end on a pin 26'.

A leaf spring 27 is secured at one end 5 within a longitudinal groove in the spindle 20, by a screw 28, and at its free end bears on the free end of the lever 26 carrying the cutting tool 25, and acts to move inwardly said lever and tool, and hold a projection 26" 10 on said lever in engagement with the spindle or pin 22, see Figs. 2 and 3.

The cylindrical box or bearing 29, to have a spiral oil channel cut therein, is mounted on the spindle 20, and bears at its inner end 15 against the bushing 14 in the stand 13. The inner ends of the yoke 23 bear against the outer end of the box or bearing 29, and hold the guide pin 22 stationary, relatively to the longitudinal movement of the spindle 20 20 carrying the cutting tool 25, and prevent any inward movement of said guide pin.

From the above description in connection with the drawings, the operation of my improvements will be readily understood by 25 those skilled in the art.

The rack bar 3 is moved to its outer position, shown in Figs. 1 and 2, and the box or bearing 29 to be operated on, is placed upon the spindle 20, see Fig. 2, the yoke 23 and the 30 guide pin 22 having been first removed, and then replaced. Power is applied to the machine, and the longitudinal inward movement of the rack bar 3 will move the spindle 6 with it, and also through the spiral shaped 35 threads 6' engaging the spiral shaped grooves in the bearing 16, will cause said spindle 6 to rotate, and with it the spindle 20, carrying the lever 26 and cutting tool 25. The longitudinal motion of the spindle 20, will cause 40 the cutting tool 25 to engage with the inner surface of the box or bearing 29, and be drawn through said box or bearing, and the rotary movement of the spindle 20, will cause a spiral shaped groove or channel 29' 45 to be cut in the box or bearing 29, see Fig. 4, which intersects the oil-hole 29".

The guide spindle or pin 22 is stationary, and also the box or bearing 29, so that as the 50 spindle 20 is drawn along through the box or bearing 29, the projection 26" on the lever 26 carrying the cutting tool 25, will pass from the reduced portion 22' see Fig. 2, up the incline 22" and onto the larger portion, as shown in Fig. 3, and force the cutting tool 55 outwardly, and cause it to engage with the inner surface of the box or bearing 29, within the end of the bearing, to cut a groove or channel in the inner surface of the box or bearing 29, see Fig. 3, which groove or channel 60 not has closed ends, as shown in Fig. 4, so that the oil cannot pass out of said channel, from the ends of the bearing.

The guide pin or spindle 22 has the enlarged portion thereof of such a length, that

it will act on the cutting tool arm 26 to move 65 it outwardly, only after the cutting tool has passed by the end of the bearing, and the reduced inner end 22" of the pin 22 will allow the cutting tool arm to move outwardly, before the cutting tool passes out of the inner 70 end of the bearing, thus cutting an oil channel or groove with closed ends.

A channel or groove may be made with open ends, by changing the position of the inclines 22" on the guide pin 22 relatively to 75 the engaging projection 26" on the lever 26, carrying the cutting tool 25.

By varying the size of the spindle 20, different sizes of boxes and bearings can be operated on, and different lengths of spiral 80 grooves or channels can be made, by varying the amount of longitudinal movement of the rack bar 3, and the channels or grooves may be cut through the ends of the boxes or bearings, if desired.

It will be understood that the details of construction of my improvements may be varied if desired.

Instead of making the spindles 6 and 20 as two separate spindles, which is the preferable construction, they may be made as a single spindle, in one part, if preferred.

Having thus described my invention, what I claim as new and desire to secure by Letters Patent is:—

1. In a machine of the class described, the combination with a longitudinally reciprocating rack, of a longitudinally movable and rotary spindle connected with said rack, a second spindle connected with the first mentioned spindle to move therewith, and carrying a movable cutting tool, and said cutting tool, a guide pin extending loosely within the spindle carrying the cutting tool, and means for holding said guide pin stationary longitudinally relatively to said spindle and said cutting tool, and said guide pin engaged by the cutting tool and moving the cutting tool into operative position, and allowing the cutting tool to be moved out of operative position.

2. In a machine of the class described, the combination with a longitudinally movable and rotary spindle carrying a movable cutting tool, and said cutting tool, of a guide pin extending loosely within said spindle, a yoke attached to said guide pin, to hold the same stationary longitudinally relatively to said cutting tool, and said pin engaged by the cutting tool during the longitudinal and rotary movement of said spindle, to move the cutting tool into operative position, and release the cutting tool, to allow it to be moved out of operative position.

WILLIAM WATTIE.
